METHOD OF MAKING CONTAINER SEALS

Ralph S. Westgate, Bloomfield, N. J., and Harry C. A. Behr, York, Pa., assignors to E. R. Squibb & Sons, New York, N. Y., a corporation of New York

Application January 11, 1928, Serial No. 246,008
Renewed September 29, 1933

5 Claims. (Cl. 113—121)

This invention relates to airtight mechanical seals for containers, particularly such seals for sheet metal ether containers the closures of which are provided with a soft metal cap so 5 as to be readily pierceable by an ordinary knife for making the contents instantly available.

In the packaging of gases or highly volatile liquids in sheet metal containers for transportation, storage, sale, and use under a considerable range of thermal conditions, it is of the utmost importance to minimize leakage at the closure and consequent contamination, waste, and danger of explosion. Sealing by means of solder has been the commonest method of accomplishing an airtight closure, but this method has been attended by numerous disadvantages: among others, the appreciable cost of solder; the necessity of performing the work by hand; the hazard of applying the hot soldering iron in the presence of the highly inflammable gas or vapors; the difficulty of assuring the absolute covering of the joint.

In an effort to avoid these disadvantages it has been proposed to effect the seal mechanically, dispensing with the solder; but closures of this type that have heretofore appeared have been of such construction as to be unable to withstand, for example, the heat of the tropics and other rigorous conditions, and do not 20 form satisfactorily even in ordinary circumstances in the temperate zone.

It is an object of this invention to provide a mechanical seal that shall be free from the defects of the soldered closure and shall further 25 more be inexpensive and virtually hermetic, so as to be proof against all adverse climatic and other unfavorable conditions, with a liberal factor of safety.

In the practice of our invention there is placed 30 on the neck of a sheet metal container a soft metal cap of such marginal conformation as to fit the upper interior of the neck and having a depending flange. A flanged hard metal ring, of similar conformation, is then superimposed 35 upon the cap. A stationary mandrel is now set upon the ring within the neck, and revolving rollers, caused to converge by the application 40 of centripetal force upon their axes, are applied to the ring flange and, by rapidly spinning thereagainst at constantly increasing speed, gradually tighten it against the exterior of the neck, the interposed soft metal serving as a 45 packing and forming an impervious joint. Access may thereafter be had to the contents of 50 the container by puncturing the center of the

soft metal cap with any sharp or pointed implement, for example, a knife or a pin, or by cutting the soft metal along the inner periphery of the hard metal ring. In contemplation of the latter procedure a suitably dimensioned inward offset is provided in the neck for seating a stopper to protect the unused portion of the contents.

The understanding of the objects, advantages, and practice of the invention will be facilitated by reference to the following specification and accompanying drawing in which

Figure 1 is a plan view of the closure cap;
Figure 2 is a plan view of the closure ring;

Figure 3 is an elevation, partly in section, of 15 a container with the cap and the ring on its neck and of the spinning apparatus in idle position;

Figure 4 is a similar view showing the closure sealed and the spinning apparatus in operative 20 position;

Figure 5 is an enlarged sectional view of a fragment of the sealed closure;

Figure 6 is an elevation showing in section a 25 sealed closure from which the central portion of the cap has been removed, with a stopper inserted and seated in the offset; and

Figure 7 is an elevation showing in section a modification of the sealed closure.

In the drawing 10 designates a container, 30 preferably of sheet metal, provided with a neck 11, preferably taper, having a shoulder 12 and a taper central offset 13. A stamped cap 14 formed of a soft metal such as lead and comprising a central circular portion 15, which may 35 be domed if desired; an annular portion 16 so inclined upwardly as to fit the interior of neck 11, and a depending flange 17, is set upon the neck 11. A ring 18 formed of a hard metal such as tin plate and having a general conformation 40 similar to that of cap 14 except that it is centrally apertured, giving a circular inner periphery 19, and having a flange 20, is now mounted upon the cap 14.

Then the container is placed under a spinning apparatus (not a part of this invention) including a stationary mandrel with a head 21 conforming in shape with the interior of ring 18 and a shank 22 surrounded by a rotatable hollow shaft 23 provided at its lower extremity 45 with a flange 24. The latter has a plurality of regularly spaced slots 25 (only one of which is shown), each receiving a taper arm 26 the bottom of which carries a rotatable roller 27 having a conical surface 28 and held in place by 50 55

a screw bolt 29. Arm 26 is pivoted below its middle point on pin 30.

This spinning apparatus is lowered until the stationary mandrel 21 is seated in ring 18. By 5 suitable means shaft 23 is now set in rotation. The centrifugal force thereby exerted upon the distal ends of arms 26 gives rise to a corresponding centripetal force at the proximal ends thereof, bringing conical surfaces 28 into firm contact 10 with flange 20. The speed of rotation is then steadily increased and causes a constantly increasing pressure by surfaces 28 against flange 20. By virtue of this accelerated rotation of shaft 23, the revolving and rotating rollers 27 15 spin the flange 20 at every point of its surface tight against neck 11, the interposed soft metal flange 17 serving as a packing throughout its area. A virtually hermetic seal is thus obtained.

Instead of the embodiment above illustrated 20 and described, forms may be constructed according to the same principle wherein a seal is provided interiorly of the neck or both exteriorly and interiorly thereof. For example, by rollers similarly operated with and against 25 the interior of ring 18, or by other suitable means, the interior of ring 18 may be spun against the interior of neck 11, the interposed annular portion 16 forming a wide, impervious seal.

30 To make the contents accessible it is necessary merely to puncture portion 15 with a sharp or pointed implement. It is generally found, however, that all the contents are not exhausted simultaneously, and it becomes desirable to safeguard the residue. Offset 13 is provided for this purpose; so that when portion 15 has been removed by cutting along periphery 19 with a knife, for example, and part of the contents poured out, a suitable stopper 31, which may be 35 an ordinary cork, is inserted into the offset 13, which is of such shape as to seat the stopper snugly, and satisfactory temporary protection is thus assured. Manifestly the diameter of periphery 19 must exceed the maximum diameter 40 of offset 13. If the full container is to be emptied at one time, the offset construction is 45 not required, and the modification shown in Figure 7 may be employed.

Containers formed with the closure herein 50 described remain impervious at the seal even though subjected to conditions far more rigorous than those encountered in transportation, storage, and use in various climates. For example, if filled with ether and immersed for 55 fifteen minutes in water maintained at a temperature of 135° F., not more than about five per cent of the cans so sealed develop any leakage. This provides a large factor of safety whereby the probability of leakage in ordinary 60 circumstances is reduced practically to zero.

Various changes may be made in the method 65 of sealing containers and in the form, construction and arrangement of parts of the container without departing from the invention or sacrificing any of the advantages thereof.

We claim:

1. The method of mechanically sealing a sheet-metal container to adapt it to hold ether 70 secure against escape, and of simultaneously providing the container with a readily pierce-

able closure, which comprises successively superposing upon the neck of the container a soft-metal cap and a hard-metal ring, each having a depending flange, and, by means of revolving and rotating rollers pressing against substantially the entire width of the ring flange, gradually spinning the flanges concomitantly towards the neck until they are closely juxtaposed thereto, thereby tightly confining the entire circumference and substantially the entire width 10 of the cap flange between the ring flange and the neck and thus providing a vapor-impervious packing, the neck of the container retaining substantially its initial form and size.

2. The method of mechanically sealing a 15 sheet-metal container to adapt it to hold ether secure against escape, and of simultaneously providing the container with a readily pierceable closure, which comprises successively superposing upon the neck of the container 20 a soft-metal cap and a hard-metal ring, each having a depending flange, and, by means of revolving and rotating rollers pressing against the ring flange, spinning the flanges towards the neck until they are closely juxtaposed 25 thereto, thereby tightly confining the cap flange between the ring flange and the neck and thus providing a vapor-impervious packing.

3. The method of mechanically sealing a sheet-metal container to adapt it to hold ether 30 secure against escape, and of simultaneously providing the container with a readily pierceable closure, which comprises successively superposing upon the neck of the container a soft-metal cap and a hard-metal ring, each having 35 a depending flange, and, by means of revolving and rotating rollers pressing against the ring flange, spinning the flanges towards the neck until they are closely juxtaposed thereto, thereby tightly confining the entire circumference 40 and substantially the entire width of the cap flange between the ring flange and the neck and thus providing a vapor-impervious packing.

4. The method of mechanically sealing a sheet-metal container to adapt it to hold ether 45 secure against escape, and of simultaneously providing the container with a readily pierceable closure, which comprises successively superposing upon the neck of the container a soft-metal cap and a hard-metal ring, each having 50 a depending flange, and spinning the flanges towards the neck until they are closely juxtaposed thereto, thereby tightly confining the cap flange between the ring flange and the neck and thus providing a vapor-impervious packing, the neck 55 of the container retaining substantially its initial form and size.

5. The method of mechanically sealing a sheet-metal container and of simultaneously providing it with a readily pierceable closure, 60 which comprises superposing upon the neck of the container a soft-metal cap and a hard-metal ring, each having a depending flange, and spinning the flanges towards the neck until they are closely juxtaposed thereto, thereby tightly 65 confining the cap flange between the ring flange and the neck.
